UNITED STATES PATENT OFFICE.

LOUIS CASPER, OF CHEYENNE, WYOMING TERRITORY.

STATION-INDICATOR.

SPECIFICATION forming part of Letters Patent No. 442,610, dated December 16, 1890.

Application filed September 12, 1888. Serial No. 285,167. (No model.)

To all whom it may concern:

Be it known that I, LOUIS CASPER, of Cheyenne, in the county of Laramie, Wyoming Territory, have invented certain new and useful 5 Improvements in Station-Indicators, of which the following is a specification.

The object of my invention is to provide a new and improved station-indicator for automatically indicating the streets, stations, and 10 other prominent points on a road as they are reached by the car.

The invention consists in the construction and combination of parts and details, as will be fully described and set forth hereinafter, 15 and pointed out in the claims.

In the accompanying drawings, Figure 1 is a front elevation of my improved station-indicator, the band being removed. Fig. 2 is a top view of the same. Fig. 3 is an elevation 20 of one end; Fig. 4, an elevation of the opposite end; Fig. 5, an enlarged detail cross-sectional view of the operating device on the axle. Fig. 6 is an end view of the same, parts being omitted. Figs. 7, 8, and 9 show separated from the device certain details of construction. The views are respectively plan, 25 front elevation, and side elevation of the toothed wheels L and L', as combined with the pawls K and K'.

Similar letters of reference indicate corresponding parts.

The casing or box A, which is hermetically sealed, is mounted loosely on the axle A², and is provided at its lower end with a weight A', 35 that holds it vertically and prevents it turning on the axle. A ring B, permanently secured on the axle, is provided with a tooth B' and a recess at each side of said tooth. On the pintle C of the casing A the polygonal 40 wheel D is mounted, which is provided at each angle with a notch D' for receiving the tooth B', the sides of the wheel D being curved on a concave line, so as to fit on the ring B. Said wheel D is provided on one side 45 with a pin or projection E, that can strike against a pivoted lever F, at each side of which a contact-spring G or G' is held, said contact-springs being connected with the line-wires a a', respectively. The swinging arm 50 F is connected with the wire b.

The station-indicator proper consists of a

casing located in such a manner in the car that it can be plainly seen. On one side plate H of said casing the two electro-magnets I and I' are provided at the bottom, the ends 55 of their cores being adjacent to and a short distance from each other. Between them the armature J is mounted to swing on a shaft J' between a bridge J² and the upright plate H of the frame. On the upper end of the armature two angular clicks or pawls K K' are pivoted, and between their upper ends a spring K² is inserted, which presses said upper ends or arms of the pawls from each other and keeps said pawls engaged with the two 60 opposite ratchet-wheels L L', mounted rigidly on the shaft J', on which the armature is mounted to swing. The wheels L L' have oppositely-arranged teeth. A fixed pin M projects from the plate H between the upper 65 ends or arms of the pawls.

The shaft J' extends longitudinally through the casing, and on its opposite end is mounted the pinion N, engaging the cog-wheel O on the same pintle with the pinion P, engaging 70 the cog-wheel Q, mounted loosely on the shaft J' and provided with a pin Q', that can act on the lower end of a lever R, pivoted on the outer side of the upright plate H', said lever being provided at its upper end with a pin 75 R' between the shanks of the fork S, on the lower end of a lever S', the upper end of which rests upon and can swing over two contact-pieces T T'.

The upper end of the lever R is provided 80 with a point that can engage a round head U on the end of the spring U' on the outer side of the upright H', for the purpose of locking the lever R in its different positions.

A ratchet-wheel V² is securely connected 85 with a cog-wheel Q, and is engaged by the end of a spring V', secured on the outside of the upright plate H'. On the shaft J' the winding-drum W is secured, and above the same a winding-drum W' is mounted. A coiled 90 spring X has the inner end secured to the shaft of the upper winding-drum W' and the outer end secured to the plate H.

Y Y' are guide-rollers for the band carrying the station-names, the ends of said bands 95 being secured to the rollers W W'. The wires a a' are connected with the opposite

magnets I I', which magnets are also connected by the wires V and V' with the switch-plates T T'.

The switch-lever S' is connected by the wire 5 m with one post of the battery Z, the other post of the battery being connected with the wire b. The spring S³ keeps the armature J midway between the heads of the electromagnets.

10 The operation is as follows: For example, if the axle carrying B' is rotated in the direction of the arrow x', the tooth B' successively passing into the notches D' of the wheel D rotates the same in the direction of 15 the arrow x², so that the pin E finally strikes against the lever F, moves the same to the right and presses it against the contact-spring G, whereby the circuit is closed. The circuit will then be as follows: From the battery Z 20 through the wire b, the lever F, the contact-spring G', the wire a', the magnet I', the wire V', switch-plate T', switch-lever S', and wire m back to the battery. The magnet I' becomes 25 excited and attracts the armature J, the upper end of which is thus swung in the direction of the arrow x³. Both pawls K K' are swung in the direction of the arrow x³, and as the upper arm of the pawl K strikes against the fixed pin M its lower end is swung from the 30 rim of the ratchet-wheel L' and clears the same. While the pawl K' is moving toward the said pin M it rotates the axle J'. As, however, the teeth on the wheel L are in an opposite direction to those on wheels L', the end 35 of the other pawl K' slides over the teeth of the ratchet-wheel L. If the armature should have moved in the opposite direction, then would the shaft or axle J' have moved in the opposite direction. When the circuit is 40 broken—that is, when the pin E has passed beyond the lever F—and the said lever hangs vertically, the springs S³, connected with the armature, bring the same into its normal position between the magnets, and thereby 45 swing the upper end of said armature in the inverse direction of the arrow x³. The pawl K', engaging the ratchet-wheel L, turns the same in the direction of the arrow x⁴. As the end of the pawl K is lifted clear of the 50 ratchet-wheel L', it cannot act on said wheel. The ratchet-wheel L being rigidly mounted on the shaft J', said shaft is also rotated in the direction of the arrow x⁴, as is also the lower drum W. Part of the band or belt carrying the station-names is thus unwound from the drum W' and wound upon the drum W, whereby a new name is exposed. By the unwinding of the band or belt from the drum W' the spring x is coiled or brought in 55 tension and serves to keep the band or belt taut at all times. In this manner the belt or band is shifted every time the wheel makes a revolution. In case the car runs in the reverse direction the direction of the rotation 60 of the wheel D will be reversed, the lever F will be pressed against the spring G', the

other circuit will be closed, the armature attracted by the magnet I, and the lower drum W revolved in the inverse direction of the arrow x⁴. Part of the belt or band is then 70 unwound from the lower drum W, and by the action of the spring X wound upon the upper drum W'. The names of the stations on the band or belt must be spaced from each other corresponding with the distance between the several stations. For instance, if two stations are three times as far from each other as the two preceding stations, the names must be arranged correspondingly on the band or belt, as the wheel D will have to 75 make three times as many revolutions in order to shift the belt sufficiently to show the last station than it had to make to show the preceding station. In case the car always runs in the same direction—that is in 80 case it is turned at the end of the line—the mechanism shown in Fig. 4 is used. Motion is transmitted from the shaft J' by means of the pinion N, cog-wheel O, and pinion P to the loose cog-wheel Q, bearing the pin Q'. 85 The sizes of said pinions and cog-wheels must be such that when the car arrives at the end of the road the wheel Q will have turned such other distance that its pin Q' can strike against and shift the lever R, which in turn 90 operates the switch-lever S', so as to throw the current from one contact T or T' to the other.

The function of the spring V⁴ is to steady the gear-wheel Q, so that the switching can 100 be perfectly made regardless of the jolting of the car.

Having thus described my invention, I claim as new and desire to secure by Letters Patent—

1. In a station-indicator, the combination, 105 with a car-axle having a ring B, provided with the tooth B', the polygonal notched wheel D, having projection E, the swinging contact-closer F, the electrical contacts G G' at the sides of the same, the casing A, surrounding the above mechanism, electro-magnets connected with the electrical contacts, a roller operated by said electro-magnets, and a band secured to the roller and bearing the 110 station-names, substantially as set forth.

2. In a station-indicator, the combination, 115 with two electro-magnets and an armature pivoted to swing between them, angular pawls pivoted to the upper end of the armature, 120 a shaft, two ratchet-wheels on said shaft, a roller on said shaft, and a band secured to said shaft and bearing the station-names, substantially as herein shown and described.

3. In a station-indicator, the combination, 125 with two electro-magnets, an armature pivoted between them, two angular pawls pivoted on the upper end of the armature, a pin projecting between the upper ends of said pawls, a spring acting on the pawls, a shaft, 130 ratchet-wheels on said shaft, on which ratchet-wheels the pawls act, a roller on said shaft,

and a band bearing the station-names and secured to said roller, substantially as herein shown and described.

4. In a station-indicator, the combination, 5 with two rollers, of a band secured to said rollers and bearing the station-names, an electro-magnet, an armature, pawls, and ratchet-wheels for operating the shaft of the lower roller, and an electric switch which is operated

by gearing of the shaft of the lower roller, substantially as herein shown and described.

In testimony that I claim the foregoing as my invention I have signed my name in presence of two subscribing witnesses.

LOUIS CASPER.
